Attleboro.

UNITED STATES PATENT OFFICE.

JOHN W. BATE, OF RACINE, WISCONSIN.

COMBINATION TOOL.

Application filed March 3, 1924. Serial No. 696,527.

This invention relates to a combined jack handle and wrench and is fully described in the following specification and shown in the accompanying drawing in which:

5 Figure 1 is a front elevation of a tool embodying the invention;

Fig. 2 is an elevation of one side of the device; and

Fig. 3 is an elevation of the other side.

10 The embodiment illustrated comprises a bar 10 having a reduced end 11 adapted to be inserted into a jack socket. This reduced portion is preferably set at an angle to the main body of the jack handle so that 15 the latter may be set for either a high or low operating position to suit the pleasure of the operator.

A hole 12 is formed in the outer end of 20 the bar 10 and sheet-metal members 13 and 14 are secured to the outer end by means of rivets 15. These sheet-metal members are raised at the center and have sockets 16 and 17 formed therein which are adapted to pass over nuts or bolt heads for the purpose of 25 turning the same. The hole 12 permits the end of the bolt, or in case of the spark plug, the upper end of the plug, to pass through, thereby acting to a certain extent as a centering means for the wrench.

30 It will be observed that the members 13 and 14 are made angular and converge toward a point beyond the outer end of the bar 10. This causes the outer end of the bar to be tilted upward and makes it easier to

insert the wrench in many of the inaccessible 35 places found about an automobile engine.

The reduced end 11 of the bar terminates in a tapered end 18 which serves as a screw-driver.

While I have shown and described certain 40 embodiments of my invention, it is to be understood that it is capable of many modifications. Changes therefore in the construction and arrangement may be made without departing from the spirit and scope 45 of the invention as disclosed in the appended claims, in which it is my intention to claim all novelty inherent in my invention as broadly as possible in view of the prior art.

I claim:

1. In a combination tool, a bar which serves as a jack handle, a sheet-metal member secured along each side of the outer end of the bar, the central portion of said members being separated from said bar, said members and bar having aligned openings, the openings in said members serving as wrench sockets.

2. In a combination tool, a bar which serves as a jack handle, a sheet-metal member secured along each side of the outer end of the bar, said members and bar having aligned openings, said members being angularly disposed with relation to the bar and converging toward the outer end of the 65 bar.

JOHN W. BATE.
